MINIATURE-GOLF GAME BOARD

John Cipyak, Lansford, Pa., assignor of seventeen and one-half per cent to Margaret Cipyak, seventeen and one-half per cent to Tekla Cipyak, seventeen and one-half per cent to Francis E. Sterner, and seventeen and one-half per cent to Anna V. Sterner, all of Lansford, Pa.

Application January 10, 1947, Serial No. 721,247

3 Claims. (Cl. 273—116)

1

This invention relates to a novel game board for use in playing a game simulating that known as "miniature golf."

An object of the invention is to provide a game which is amusing and entertaining, and which involves skill and patience in the playing thereof.

A further object of the invention is to provide a game board of the above kind formed with depressed apertured golf course sections upon which a rolling game piece is to be moved by skillful tilting of the board from the horizontal.

Another object of the invention is to provide a game board of the above kind in which provision is made for collecting the game pieces which pass through trap-simulating openings separately from those which pass through cup-simulating openings, thereby facilitating scoring of points during playing of the game.

Still another object of the invention is to provide a game board of the above kind which is relatively simple in construction and which can be manufactured at a relatively low cost.

The exact nature of the present invention will become apparent from the following description when considered in connection with the accompanying drawings, in which:

Figure 1 is a top plan view of the game board constructed in accordance with the present invention;

Figures 2 and 3 are sections taken respectively on line 2—2 and on line 3—3 of Figure 1; and

Figure 4 is a fragmentary vertical section taken on the line 4—4 of Figure 3.

Referring in detail to the drawings, the present game board includes a rectangular tray A having a flat bottom 10 formed at the edges with right angularly disposed side walls 11 and end walls 12.

Spaced horizontal decks 13 and 14 are rigidly supported within the tray A between the top and bottom of the latter, and said decks extend the full width of the tray and from one end of the latter to a point adjacent but spaced from the other end thereof. Each deck preferably has depending walls 15 and 16 at the edges thereof which rest upon the bottom wall 10 of the tray to support the decks at the proper elevation, the deck 14 being nested within the lower portion of deck 13. A vertical wall 17 divides the spaces above and below the decks from the space at said other end of the tray so that the latter space provides a collection chamber for spherical game pieces 18a, within the tray. The vertical wall 17 and the adjacent depending walls 15 and 16 of the decks have superposed exit openings therein

2

at 18 and 18' and near one end of said wall 17 for passage of the game pieces from the spaces beneath the respective decks to said chamber. Strips 19 and 20 divide said chamber into separate game piece receiving compartments 21 and 22 which communicate with the respective exit openings at 18 and 18', and said strips have elevated horizontal portions 23 arranged in the same plane and in spaced tandem relation within the collection chamber, and inclined portions 24 for leading the game pieces upwardly from each of said openings at 18 and 18' to the associated elevated portions 23 when the board is tilted laterally in one direction. This facilitates delivery of the game pieces at elevated points within the compartments 21 and 22 for convenient removal therefrom. The upper deck 13 has separated depressed areas 25 which simulate the sections or "holes" of a miniature golf course and which are numbered as at a to denote the successive sections of the golf course in the order that they are to be negotiated, as well as being located to indicate the "tee" position for the respective sections. Within each section 25 the upper deck 13 is provided with an opening 26, preferably circular, simulating the cup of the section. Also, within each section the deck 13 is provided with at least one other opening 27 representing a trap. There is a fairway surface 28 within each section between the "tee" position a and the cup simulating opening 26 thereof. This fairway surface may be formed by a flat portion of the surface of deck 13 within each depression, or a groove in the top of a member 29 secured within a depression or depressions and having an inclined upper surface so as to simulate the condition presented by a hill or hilly portion within the section of the course. The groove 28 is of a size to form a runway for the game pieces 18a in passing from the tee position to the cup simulating opening. In one or more cases, a tunnel member 30 may be provided within a depression or depressions through which the game pieces must be rolled in passing from the tee position or positions to the cup simulating hole 26 or holes.

Means are provided for conducting the game pieces from the cup simulating openings 26 to the space beneath the lower deck 14, such as upstanding tubular members 31 provided on the lower deck 14 in vertical alignment with the openings 26 and corresponding openings provided in said lower deck 14 as clearly shown in Figures 2 and 4. The trap-simulating openings 27 provide for passage of the game pieces into the space between the decks 13 and 14.

The game may be played as follows:

A movable game piece 18a is positioned at the tee position a indicated by the numeral 1 in the first section of the golf course, and by inclining the board, said game piece is rolled toward the cup-simulating opening 26 of this section of the course. The object is to carefully manipulate the board so as to cause the game piece to not pass through the trap-simulating opening or openings at 27 and to pass through the cup-simulating opening at 26. As the game pieces which pass through cup-simulating openings 26 will collect in the compartment 22, and as those which pass through the trap-simulating openings 27 will collect in the compartment 21, accurate scoring of the game is facilitated. This operation is repeated in connection with each of the succeeding sections of the golf course by the same player. The same procedure is then followed by another player, and the player succeeding in causing passage of the greater number of game pieces through cup-simulating openings wins the game. Care must be taken to prevent a game piece from rolling out of the depressed golf course sections, and skillful manipulation of the board is necessary to negotiate the fairways without causing passage of the game pieces through the trap-simulating openings.

The game can also be played by two or more players, each player playing one hole at a time. Thus, a player will continue trying until he succeeds in rolling the game piece into the cup-simulating hole of a section of the course, the game piece being returned to the tee position of such section each time it passes into a trap-simulating opening, and one stroke being counted for each try. After all players have rolled the ball into the cup-simulating hole of this section, they proceed to and successively play the next section of the course. When all sections of the course have been played, the player requiring the least number of tries or "strokes" for the course wins.

It is to be understood that the form of my invention herein shown and described is to be taken as a preferred example of the same, and that various changes as to the shape, size and arrangement of parts may be resorted to without departing from the spirit of the invention as claimed.

What I claim is:

1. A miniature-golf game board comprising a rectangular tray, a plurality of only two spaced horizontal decks rigidly supported one above the other within said tray between the top and bottom of the latter, said decks extending the full width of the tray and from one end of the latter to a point adjacent but spaced from the other end thereof, a vertical wall dividing the spaces above and below said decks from the space at said other end of the tray, and strips dividing the

latter space into two separate collection chambers for spherical game pieces, said vertical wall having superposed exit openings therein near one end for passage of game pieces from the spaces beneath the respective decks to the respective collection chambers, the upper deck having a plurality of depressed areas simulating the sections of a golf course and being provided with a cup simulating opening and a trap simulating opening in each depressed area, and means to conduct game pieces from certain of said openings through the lower deck.

2. A miniature-golf game board comprising a rectangular tray, spaced horizontal decks rigidly supported within said tray between the top and bottom of the latter, said decks extending the full width of the tray and from one end of the latter to a point adjacent but spaced from the other end thereof, a vertical wall dividing the spaces above and below said decks from the space at said other end of the tray so that the latter space provides a collection chamber for spherical game pieces, the upper deck having a plurality of openings, means to conduct game pieces from certain of said openings through the lower deck, said vertical wall having superposed exit openings therein near one end for passage of game pieces from the spaces beneath the respective decks to said chamber, strips dividing said chamber into separate game piece receiving compartments communicating with the respective exit openings, and said strips having elevated horizontal portions arranged in the same plane and in spaced tandem relation within said chamber and inclined portions for leading the game pieces upwardly from each of said openings to the associated elevated portions when the board is tilted laterally.

3. The construction defined in claim 1, wherein in the cup-simulating openings are of circular form and the trap-simulating openings are of non-circular form, the lower one of said decks having openings aligned with the cup-simulating openings of the upper deck, and tubular members carried by the lower deck and providing the means for conducting the game pieces from the cup-simulating openings to the space beneath the lower deck, the trap-simulating openings providing for passage of the game pieces into the space between the decks.

JOHN CIPYAK.
